UNITED STATES PATENT OFFICE.

UTLEY WEDGE, OF ARDMORE, PENNSYLVANIA.

ROASTING-FURNACE.

939,881.

Specification of Letters Patent.

Patented Nov. 9, 1909.

Application filed February 24, 1909. Serial No. 479,736.

To all whom it may concern:

Be it known that I, UTLEY WEDGE, a citizen of the United States, residing in Ardmore, Pennsylvania, have invented certain 5 Improvements in Roasting - Furnaces, of which the following is a specification.

My invention relates to that class of roasting or like furnaces which have superposed hearths, and a central shaft provided with 10 arms carrying stirring and feeding blades or rabbles disposed in the different working chambers, the ore or other material to be treated (hereinafter, for convenience, referred to as "ore") being fed into the furnace at the top and, after being properly treated in its passage through the furnace, being discharged from the bottom.

The object of my invention is to provide 20 for the proper feeding of the ore without permitting any escape of the gases at the top of the furnace. This object I attain in the manner hereinafter set forth, reference being had to the accompanying drawings, in which—

25 Figure 1 is a view, partly in vertical transverse section and partly in elevation, of a furnace constructed in accordance with my invention; Fig. 2 is a plan or top view of said furnace; Fig. 3 is an enlarged transverse section on the line *a—a*, Fig. 2; Fig. 4 is a horizontal section of part of the furnace structure; Fig. 5 is a similar view illustrating a somewhat different construction from that shown in Fig. 4; and Fig. 6 is a view 30 similar to the upper part of Fig. 1, but illustrating another embodiment of my invention.

In the drawings, 1 represents the outer wall of the furnace, 2 the hearths, and 3 35 the arches of the successive working chambers and 4 the central hollow shaft carrying the radial arms 5 which project into the working chambers and are intended to carry stirring and feeding blades or rabbles, not 40 shown in the drawing, whereby the material delivered into the upper working chamber is caused to travel therefrom through the successive chambers below, the various chambers being in communication with one 45 another through passages 6.

Secured to the outside of the shaft 4 are 50 angular bars 7 upon which are supported the refractory blocks 9 whereby said shaft is protected from the heat of the furnace, 55 the bars 7 having ribs or flanges 10 upon

their horizontal members which ribs or flanges are contained in grooves or recesses in adjoining faces of the blocks 9, as shown in Fig. 1, so that while said blocks are both supported vertically upon and confined 60 radially to the shaft 4, no part of any of the bars 7 is exposed directly to the heat of the furnace, the burning out of said bars being thereby prevented and the necessity for their relatively frequent renewal being 65 overcome.

The tiles 11 which support the inner portions of the hearths 2 of the respective working chambers of the furnace are provided with vertical flanges 12 which project above 70 the level of the hearth and thereby tend to prevent the ore on any hearth of the furnace from gaining access to the annular space between the tiles 11 and the protecting blocks 9 which surround the rotating shaft 4, and 75 certain of the latter blocks have outwardly projecting beveled flanges 13, whereby, if any portion of the ore upon either hearth of the furnace does find its way to the space between the tiles 11 and the protecting blocks 80 9, it will, after falling through said space, be deflected by the beveled flange 13 into the working chamber below that from which it has escaped and will therefore be prevented 85 from finding its way into the final or finishing chamber of the furnace, consequently there will be no admixture of raw or partially treated ore with the finished ore in said final chamber.

In order to prevent access of air to the 90 working chambers around the lower end of the central shaft of the furnace said shaft is provided with an annular trough 14 preferably formed in one piece with the lowermost angle bar 7 which supports the refractory 95 casing of the shaft and into this trough dips a depending flange 15 on the metallic deflector 12^a with which the inner portion of the lowermost hearth 2 of the furnace is provided. The trough 14 is normally filled 100 with water up to a level above the bottom of the flange 15 so as to seal said flange and prevent the flow of air inwardly past the same, water being supplied to the trough in any available way, as, for instance, by the 105 discharge pipe 16 which conveys the cooling water from the stirrer arm 5 in the lowermost chamber of the furnace, the water, when it has reached the proper level in the trough 14, escaping therefrom through one 110

or more overflow pipes 17 through which it is discharged into an annular gutter 19, communicating with a sewer pipe 20.

The previously described features of construction of the furnace are not herein claimed as they form the subject of a separate application for Letters Patent.

The roof of the furnace constitutes a storage bed and heater or drier for the green ore, said roof being, by preference, composed of an outer bed 21 and an inner bed 22, the latter being at a lower level than the outer bed, and providing a passage 23 around the refractory casing of the shaft 4, through which passage the ore may be fed into the uppermost chamber of the furnace.

Secured to the upper end of the shaft 4 is a transverse beam 24 which projects outwardly over the roof of the furnace, said beam having, at each end, bearings for a rock shaft 25 which has projecting arms 26 carrying a bar 27 with depending blades or rabbles 29, the latter acting upon the mass of green ore lying upon the outer bed 21 of the roof of the furnace and serving to stir said mass of ore and also to gradually feed the same inwardly onto the lower bed 22 of the roof, the bar 27 for the latter purpose being slightly inclined in respect to a radial line, as shown in Fig. 2. The rabbles 29 simply trail along on the top of the mass of ore on the bed 21 of the furnace roof, being held in contact with the same only by their weight and being free to rise when they meet with any obstruction which opposes undue resistance to their forward movement.

Mounted on the shaft 4 below the transverse beam 24 is an annular plate 30 with depending edge flange 31, the latter projecting into the mass of powdered ore upon the inner bed 22 of the furnace roof and being luted thereby so as to prevent any escape of gas around the shaft 4 at the top of the furnace. At one or more points the flange 31 is cut away so as to provide an opening 31^a through which ore can be fed from outside to inside of the flange, said feeding of the ore being effected by suitable depending blades or rabbles 32 rigidly secured to the transverse beam 24, as shown in Fig. 1.

Mounted upon the annular plate 30 is a box 33 in which is vertically guided a blade 34, this blade being adjustable vertically in the box 33 and secured in position after adjustment by set screws 35 or other suitable means, the lower portion of the blade projecting below the plate 30 and acting upon the mass of ore upon the inner bed 22 so as to feed the same into the space 23 surrounding the upper portion of the shaft casing from which it passes into the upper chamber of the furnace, the blade 34 being disposed at the proper angle to effect such feeding of the ore, and the volume of feed being determined by the vertical adjustment of

the blade, so as to cause it to extend to any desired depth into the mass of ore lying on the bed 22. The upper portion of the box 33 is hopper-shaped and contains luting material 36 (see Fig. 3) for preventing any escape of gas alongside of the blade 34.

Instead of providing feeding blades or rabbles 32 for forcing the ore through openings in the flange 31, the ore may be permitted to flow by gravity through such opening or openings as shown, for instance, in Fig. 5, or the openings may be dispensed with altogether and the blade 34 may only act upon the ore which flows in under the edge of the flange 31.

Instead of rotating the blade 34 through a mass of ore contained upon a fixed bed 22 the ore may, if desired, be fed by the rabbles 29 from a storage bed onto a delivering bed mounted upon and rotating with the shaft 4, as shown for instance in Fig. 6, the delivery bed, in the latter case, consisting of an annular plate 22^a, secured to the shaft and the blade 34 being mounted upon the under side of a plate 21^a which constitutes the storage bed, but being, by preference, adjustable from and toward the shaft 4 by means of a rod 40 so as to cause it to project more or less into the mass of ore deposited by the rabbles 29 upon the inner portion of the bed 22^a and thereby regulate the volume of ore which is being fed into the furnace. In the structure shown in Fig. 6 the luting of the joint between the rotating and non-rotating members of the furnace is effected without the formation of a flange as in the structure shown in Fig. 1.

I claim:

1. The combination of the fixed structure of a furnace, a rotating shaft therein, and an external ore-luted feeding device having, as an element, a plate carried by said rotating shaft.

2. The combination of the fixed structure of a furnace, a rotating shaft therein, and an ore-luted feeding device having, as an element, a plate carried by said rotating shaft, and embedded in the mass of ore.

3. The combination of the fixed structure of a furnace, a rotating shaft therein, and an external ore-luted feeding device having, as elements, a plate carried by said rotating shaft, means for removing portions of the mass of ore which forms the lute, and means for replenishing the same.

4. The combination of the fixed structure of a furnace, a rotating shaft therein, and an ore-luted feeding device having, as elements, a plate carried by said rotating shaft, means for removing portions of the mass of ore which forms the lute, and feeding them into the furnace through a roof opening surrounding the shaft, and means for replenishing the mass of ore which forms the lute.

5. The combination of the fixed structure

of a furnace, a rotating shaft therein, and an ore-luted feeding device having, as elements, a plate carried by said rotating shaft, a feeding device mounted upon said plate 5 and serving to remove portions of the mass of ore which forms the lute and feed them into the furnace through a roof opening surrounding the shaft, and means for replenishing the mass of ore which forms the lute.

10 6. The combination of the fixed structure of the furnace, a rotating shaft therein, and an ore-luted feeding device having, as elements, a plate carried by said rotating shaft and embedded in the mass of ore, a feeding 15 device mounted upon said plate and serving to remove portions of the mass of ore which forms the lute and feed them into the furnace through a roof opening surrounding the shaft, and means for replenishing, the 20 mass of ore which forms the lute.

7. The combination of a furnace having a roof with an ore storing and drying bed thereon, and a bed which receives the ore from said storage bed and delivers it to the 25 furnace.

8. The combination of the fixed structure of a furnace having a roof with an ore storing and drying bed thereon, and a bed at a lower level than said storage bed but 30 receiving the ore from the latter and delivering it to the furnace.

9. The combination of the fixed structure of a furnace having a roof with an ore storing and drying bed thereon, a bed for receiving the ore from said storage bed and delivering it to the furnace, means for conveying the ore from the storage bed to the delivery bed, and means for conveying the ore from said delivery bed to a treating 40 chamber of the furnace.

10. The combination of the fixed structure of a furnace having a roof with an ore storing and drying bed thereon, an ore delivery bed at a lower level than said storage bed, means for conveying the ore from the storage bed to the delivery bed, and means for conveying the ore from said delivery bed to a treating chamber of the furnace.

11. The combination of a furnace having 50 ore storing and delivery beds at the top of the furnace, means for directing the ore from said delivery bed to a working chamber of the furnace, and means whereby the body of ore is caused to form a lute for preventing escape of gas at the top of the furnace.

12. The combination of the fixed structure of a furnace, a central rotating shaft therein having a feed opening around the same, and a luted ore-feeding device at the top of the furnace which prevents escape of gas around said rotating shaft.

13. The combination of the fixed structure of a furnace, a rotating shaft therein

having a feed opening around the same, an 65 ore-feeding device at the top of the furnace, and means whereby a body of ore stored upon the roof of the furnace is caused to lute said feeding device against the escape of gas around said rotating shaft. 70

14. The combination of the fixed structure of a furnace, a rotating shaft therein, and a plate carrying a blade for feeding into the upper working chamber of the furnace, a mass of ore lying upon a bed at the 75 top of the furnace, said plate having a portion embedded in said mass of ore, which thus acts as a lute to prevent the escape of gas at the top of the furnace.

15. The combination of the fixed structure of a furnace, a rotating shaft therein, a plate having a depending flange embedded in a mass of ore at the top of the furnace, and an ore-feeding blade carried by said plate. 80

16. The combination of the fixed structure of a furnace, a rotating shaft therein, a plate having a depending flange embedded in the mass of ore at the top of the furnace, and an ore-feeding blade carried by said 85 plate, said flange having an opening therein to permit flow of the ore to the space beneath the plate.

17. The combination of the fixed structure of a furnace, a rotating shaft therein, a plate having a depending flange embedded in the mass of ore at the top of the furnace, and having an opening therein, an ore-feeding blade carried by said plate, and means outside of the flange for feeding the ore 95 through the opening therein. 100

18. The combination of the fixed structure of a furnace, a rotating shaft therein, an ore delivery bed at the top of the furnace, a plate adapted to coöperate with the 105 mass of ore on said bed to form a lute for preventing escape of gas at the top of the furnace, an ore-feeding blade carried by said plate, and ore-feeding devices outside of the plate for feeding the ore to the delivery bed. 110

19. The combination of the fixed structure of a furnace, a rotating shaft therein, an ore delivery bed at the top of the furnace, a plate adapted to coöperate with the mass of ore on said bed to form a lute for preventing escape of gas at the top of the furnace, an ore-feeding blade carried by said plate, and ore-feeding devices outside of said plate for feeding the ore to the delivery bed, said ore 120 feeding devices being free to rise and fall as they travel over the mass of ore. 115

20. The combination of the fixed structure of a furnace, a rotating shaft therein, an ore delivery bed at the top of the furnace, a plate adapted to coöperate with the mass of ore on said bed to form a lute for preventing escape of gas, an ore-feeding blade carried 125

by said plate, and ore-feeding devices outside of said plate, some of said ore feeding devices being yielding and others rigid.

21. The combination of the fixed structure of a furnace, having a roof with outer bed on a higher plane than an inner bed, a rotating shaft, a plate adapted to form, with the mass of ore on the inner bed, a lute for preventing the escape of gas, and an ore-feeding blade carried by said plate.

22. The combination of the fixed structure of a furnace, having a roof with outer bed on a higher plane than an inner bed, a rotating shaft, a plate adapted to form, with the mass of ore on the inner bed, a lute for preventing the escape of gas, an ore-feeding blade carried by said plate and ore-feeding blades adapted to act upon the mass of ore on the elevated outer bed.

23. The combination of the fixed structure of a furnace, having a roof with outer bed on a higher plane than an inner bed, a rotating shaft, a plate adapted to form, with the mass of ore on the inner bed, a lute for preventing the escape of gas, an ore-feeding blade carried by said plate, ore-feeding blades adapted to act upon the mass of ore on the elevated outer bed, and an ore-feed-

ing blade acting on the ore on the lower bed, and serving to feed said ore into position to be engaged by the feeding blade which is mounted on the luting plate.

24. The combination of the fixed structure of the furnace having a roof with ore-delivery bed thereon, a rotating shaft, and a plate carried by said shaft and luted by the mass of ore on the delivery bed, said plate carrying a blade which feeds the ore from the delivery bed into the furnace.

25. The combination of the fixed structure of the furnace having a roof with ore storage and delivery beds thereon, a rotating shaft, a plate carried by said shaft, and luted by the mass of ore, a blade carried by said plate and serving to feed the ore from the delivery bed into the furnace, and means also carried by the rotating shaft for conveying the ore from the storage bed to the delivery bed.

In testimony whereof, I have signed my name to this specification, in the presence of two subscribing witnesses.

UTLEY WEDGE.
